UNITED STATES PATENT OFFICE.

WILLIAM F. HENDRY, OF OSSINING, NEW YORK, ASSIGNOR TO MANHATTAN ELECTRICAL SUPPLY COMPANY, INCORPORATED, OF NEW YORK, N. Y., A CORPORATION OF MASSACHUSETTS.

LOUD SPEAKER.

Application filed August 14, 1924. Serial No. 732,002.

This invention relates to loud speakers, and more particularly to an improved sound amplifying structure adapted for use in telephone receivers, phonograph reproducers, or the like.

As well known, sound reproducers used in receivers and phonograph reproducers comprise a diaphragm responsive to electrically or mechanically transmitted vibrations corresponding to variations of the voice currents, and generate air current variations corresponding to the sounds to be reproduced. Two types of diaphragms have become generally known, one type is of some thin magnetic or non-magnetic material such as a thin sheet of iron or mica and is held taut, and the other type has a relatively large and loosely vibrating surface. The small, tightly stretched diaphragm is particularly responsive to the high notes of the scale and the large, loosely supported diaphragm to the lower notes of the scale. Sound reproducers designed to reproduce faithfully the lower notes are usually unsatisfactory for the reproduction of higher notes, and those particularly designed for the reproduction of the higher notes fail to respond to the lower notes.

It is the object of the present invention to provide a sound reproducing structure of more universal characteristics, and one which will properly respond to the notes of the lower and higher scales.

With this object in view I provide a sound reproducing device which comprises a relatively small, taut diaphragm and also a large, loose diaphragm, both diaphragms being operated by a common mechanism.

In accordance with one of the features of the present invention, the operating mechanism consists of the armature of an electromagnet so proportioned and adjusted that during its operation relatively slight movements are imparted to the large, and relatively large movements to the small diaphragms.

The drawing represents a plan view partly in section of a telephone loud speaker embodying the features of the present invention.

The magnet structure is of substantially the same type as described in my copending

application Serial No. 725,036, filed July 9, 1924, and consists of two permanent U-shaped magnets 1 and 2 positioned with their like pole pieces opposite each other and held together by means of a bolt 3 against a spacer of non-magnetic material. Pole pieces NN and SS form integral parts of plates 4 and 5 held against the legs of the permanent magnets by means of the above mentioned spacer. Two coils 6 and 7 are frictionally held between, but insulated from the plates 4 and 5. These coils surround an armature 8 which is supported between the pole pieces on a resilient wire 9 which in turn is held taut between the plates 4 and 5 by means of nuts 10 and 11 engaging suitable slots provided in the plates 4 and 5. The wire 9 is attached to the armature 8 between the two coils 6 and 7 and near the center of the armature. Adjacent to the point at which the wire 9 is attached to the armature and slightly off center, a strut 12 is fastened to the armature 8 and projects therefrom through a slot 13 provided in plate 5. The free end of the strut 12 is attached by means of suitable washers 14 to the apex of a large paper diaphragm 15. The paper diaphragm is in the form of a double cone one end of which is cut away, and is carried by a ring 16. The ring 16 is supported on a bracket 17 carrying also arms 18 and 19 on which the magnet structure is mounted. The bracket 17 is fastened to an upright 20 projecting from a base 21. The strut 12, being near the point of suspension or pivot point of the armature 8, will perform only relatively slight movements when, in response to variations in the electric current traversing coils 6 and 7, the armature 8 is caused to vibrate between the pole pieces N and S. These slight movements of the strut 12, however, are sufficient to cause displacements of the large diaphragm 15 that result in the reproduction of speech.

Another strut 22 is attached to the armature 8 at a greater distance from its center of rotation. The strut 22 passes through a notch cut in one of the N pole pieces bent out of plate 4. The end of the strut 22 is fastened by suitable means to a taut metallic diaphragm 23 clamped between a ring 24

mounted on bracket 17 and a casing 25 which screws on the ring 24. Through the longer leverage insured by the strut 22, the movements of the armature 28 are translated into vibrations of relatively large amplitude of the metal diaphragm 23, and these are amplified by means of a suitable horn 26 with which the diaphragm 23 communicates through an opening 27 in the casing 25.

10. What I claim is:

1. In a sound reproducer, an arm pivoted near the center and vibrated in accordance with the sounds to be reproduced, two struts attached to said arm, one near its center and 15 the other near its end, and two diaphragms, one responsive to high and the other to low notes operated by said struts.

2. In a loud speaker, an armature supported near its center, magnetic means acting on both ends of said armature, a taut and a loose diaphragm, a strut having one end attached to said armature near its center and the other end to said loose diaphragm, and another strut having one end 25 attached to said armature far from its center and the other end to the taut diaphragm.

3. In a telephone loud speaker, an armature supported near its center, magnetic means acting on both ends of said armature, 30 a large and a small diaphragm, a strut having one end attached to the armature near its center and the other end to the large diaphragm, and another strut having one end attached to the armature far from its

center and the other end to the small diaphragm.

4. In a telephone loud speaker, an armature resiliently supported near its center, a magnetic field acting on both ends of said armature, a relatively large and loosely supported diaphragm, a relatively small tightly stretched diaphragm, a strut having one end attached to the armature near its point of suspension and the other end to said large diaphragm, and another strut having one end attached to said armature at a relatively great distance from its point of suspension and the other end to said small diaphragm.

5. In a telephone loud speaker, an armature resiliently supported near its center, two pole pieces adjacent each end of said armature, two coils surrounding said armature on the two sides of its point of suspension and between said two pole pieces, a relatively large and loosely supported cone-shaped paper diaphragm, a strut having one end attached to the apex of said diaphragm and near its point of suspension, a relatively small tightly stretched metallic diaphragm, and a strut having one end attached near the center of the metal diaphragm and the other end to said armature outside of said coils and over one of said pole pieces.

In testimony whereof, I have signed my name to this specification this 12th day of August, 1924.

WILLIAM F. HENDRY.
